Primary Examiner — Deanna L Fluegeman(74) *Attorney, Agent, or Firm* — Schwegman, Lundberg & Woessner, P.A.(57) **CLAIM**

The ornamental design for a display with graphical user interface, as shown and described.

DESCRIPTION

A portion of the disclosure of this patent document contains material which is subject to copyright protection. The copyright owner has no objection to facsimile reproduction by anyone of the patent document or the patent disclosure, as it appears in the Patent and Trademark Office patent file or records, but otherwise reserves all other copyright rights whatsoever. The following notice applies to the drawings that form a part of this document: Copyright © 2010 Adobe Systems Incorporated.

FIG. 1 is a face view of a display with graphical user interface, showing my new design;

FIG. 2 is an annotated face view of the design of FIG. 1; FIG. 3 is an enlarged face view of a first portion of the design of FIG. 1, indicated by 'A' in FIG. 2;

FIG. 4 is an enlarged face view of a second portion of the design of FIG. 1, indicated by 'B' in FIG. 2;

FIG. 5 is an enlarged face view of a third portion of the design of FIG. 1, indicated by 'C' in FIG. 2;

FIG. 6 is an enlarged face view of a fourth portion of the design of FIG. 1, indicated by 'D' in FIG. 2; and,

FIG. 7 is an enlarged face view of a fifth portion of the design of FIG. 1, indicated by 'E' in FIG. 2.

Subject matter shown in broken lines, including all text, forms no part of the claimed design.
